UNITED STATES PATENT OFFICE.

WALTER S. FISHER, OF TOLEDO, OHIO, ASSIGNOR TO THE WILLYS-OVERLAND COMPANY, OF TOLEDO, OHIO, A CORPORATION OF OHIO.

PISTON.

Application filed July 18, 1923. Serial No. 652,302.

The present invention relates to pistons, and has for its object to improve the construction of pistons of the split skirt type used in gas engines and the like, whereby to 5 increase their efficiency and prolong their length of service.

Split skirt aluminum pistons employed in cast iron cylinders frequently cause piston "slap" after a considerable period of use. 10 Apparently the skirt of the piston rolls inwardly somewhat under the influence of heat and pressure long continued, and takes a permanent set with a diameter less than that of the cylinder. A solid iron ring 15 mounted within the piston at the lower end of the skirt in such a way as to permit the skirt to expand with respect to the ring, thus tending to close up the space left by the split in the skirt, will cure the trouble, be- 20 cause the solid iron ring will act as a reinforcement to prevent the rolling in or distortion of the skirt.

One object of my invention is to provide a new and improved method of applying 25 such reinforcement to the skirt of a split skirt piston.

Another object is to provide a new and improved method for bringing the diameter of the lower portion of the split skirt to 30 an accurate dimension readily and quickly, without extreme care in machining.

A further object is to provide new and improved means for practicing the method disclosed herein.

To these and other ends, the invention embodies different novel features of construction and arrangement of parts, which will be more fully described and claimed herein- 45 after.

A disclosure constituting one embodiment of the invention, is illustrated in the accompanying drawings, in which:

Figure I is a vertical section of an engine cylinder containing a piston constructed in 50 accordance with my invention.

Fig. II is a fragmentary section of the lower end of the piston, with the reinforcing parts omitted.

Fig. III is a sectional plan taken on line 55 III-III of Fig. I.

Fig. IV is a detail perspective view of the expansive ring shown in Fig. I.

Fig. V is an enlarged detail section taken on line V-V of Fig. II.

Fig. VI is an enlarged detail section taken 60 on line VI-VI of Fig. I.

Fig. VII is a sectional elevation through the piston and holder therefor, including the means for effecting the proper expansion of the piston skirt, the section being taken on 65 line VII-VII of Fig. VIII, and

Fig. VIII is a top plan view of the piston and holder shown in Fig. VII.

In maintaining a uniform diameter for the piston, determined by the running clearance therefor, I provide what is, in effect, a solid reinforcing ring within the lower end of the split skirt. The ring is made 70 of the same material as the cylinder walls, which usually are of cast iron or steel, and therefore has the same co-efficient of expansion as the cylinder walls. The slotted skirt of the aluminum alloy piston, having a greater co-efficient of expansion than the ring, will tend to creep around the ring 75

without becoming distorted and without varying the diameter of the piston. If the solid ring were omitted, the slotted skirt would tend to close in or collapse, due to the thrust on the skirt of the piston in operation. In this way, the piston skirt would 80

become distorted, taking a permanent set and resulting in a reduced diameter, thus increasing the "slap" and permitting the passage of excessive quantities of oil to the 85 combustion chamber. Furthermore, excessive wear on the wrist pin and other parts would thus result, and the efficiency of the engine be considerably decreased. By the

use of the substantially solid cast iron or 90 steel ring, the expansive properties of which conform closely to those of the cylinder, the original shape and diameter of the piston is more accurately maintained and the objections pointed out above are avoided.

The method disclosed herein, by which the uniformly correct diameters of the pistons are obtained, and the means by which the piston skirt is reinforced and held 95 against distortion, constitutes a marked im-

provement in piston construction and affords a practical and economical form of piston, tending to increase the efficiency of the engine and therefore reducing the cost of operation.

In carrying out my improved invention, I employ a piston 10 constructed in any approved manner and including a split skirt portion 11, suitable piston rings 12, and 10 wrist pin bores 13, all as shown in Fig. I, the piston being shown within a cylinder 14 which forms no part of the present invention. Openings 15 are provided in the wall of the piston for rendering accessible 15 the bolts for securing the connecting rod with the wrist pin (not shown).

The skirt 11 may have one or more longitudinally disposed slots 16 therein, being preferably constructed with one only, as shown. 20 Near the bottom of the skirt is formed an annular groove 17, adapted to receive an expandible ring 18, having its free ends beveled as indicated at 19 in Fig. IV. A recess 20 is formed in the skirt of the piston for 25 the reception of a wedge 21, adapted to be driven between the beveled portions 19 of the ring to effect the desired expansion of the skirt. Other suitable expanding means for the ring, adapted for rigid connection 30 with the piston, may be employed, if desired. The wedge or expanding member, when forced inwardly between the ends of the split ring the desired amount, is directly connected with the piston, preferably 35 by means of a rivet 22 or similar retaining member inserted in registering openings formed in the wedge and piston after the parts are assembled. One of said openings is indicated at 23 in Figs. II and V, which 40 may be formed in the piston before the application of the expanding device thereto, if desired.

The present method involves the insertion of the expandible ring within the 45 groove 17; the application to the ring of an expanding device, such as the wedge 21; the mounting and securing of the piston and expanding parts in a suitable holder or gauge, such as 24, having the desired diameter or having suitable limiting portions 50 to determine the expansion of the piston; the application of pressure to the expanding wedge, as by means of the screw 25; the forming of one or both of the openings for 55 the reception of the retaining member 22 after the expanding member has been forced to the desired position; and the subsequent insertion and securing of the retaining member 22 in the openings.

60 The piston is preferably held firmly within the holder by a pin 26 insertable through the wall of the holder and through the oppositely disposed wrist pin bores 13 as shown in Fig. VIII. After the screw 65 25 has been tightened to move the expand-

ing member 21, in order to force the walls of the piston skirt into engagement with the inner wall of the holder 24, a suitable tool, such as a drill, is inserted through the opening 27 of the holder and rotated to form the 70 registering openings in the piston and retaining ring. As before stated, the opening 23 may be formed previous to the application of the retaining device, if desired. The rivet 22 or other suitable retaining member 75 is then inserted and secured, to permanently hold the expanding member in position.

The screw 25, threaded through the extension 28 of the holder, is preferably provided with a relatively movable portion 29, 80 adapted to seat upon the wedge 21 as shown in Fig. VII, the connection between the screw and member 29 being preferably in the form of a ball and socket joint.

The screw 25 may be employed, upon removal of the pin 26, to force the piston from the holder 24, should the expansion of the piston result in its sticking to the holder.

The holder is provided with a flat portion 30 adapted for seating upon a suitable 90 abutment carried by a table or frame for supporting the holder (not shown). In this way, the holder is prevented from turning when the piston and wedge are being drilled and when the rivet is applied for 95 securing the wedge upon the piston.

While the construction herein shown and described is well adapted to fulfill the objects of the invention, it is to be understood that changes in the form, proportions, arrangement of parts and details of construction shown, may be resorted to when found expedient, without departing from the spirit of the invention as expressed in the 100 claims.

I claim as my invention:

1. The method of dimensioning the skirt of a split skirt piston having a groove formed internally therein, which comprises inserting a divided expandible ring within 110 the groove, forcing a wedge along the inner surface of the skirt between the ends of the ring to obtain the desired expansion, thereafter forming registering openings in the wedge and piston and subsequently inserting a retaining member for the wedge formed to fit tightly in said openings.

2. The method of dimensioning the skirts of split skirt pistons for internal combustion engines and the like, which comprises inserting an expandible ring within the piston, applying an expanding device thereto, mounting the piston and expanding device in a holder having a bore corresponding 120 substantially in diameter to that of the cylinder in which the piston is to operate, applying pressure to the expanding device until the diameter of the piston is equal to that of said bore, and thereafter affixing the expanding device non-adjustably to the 125 piston.

piston without removing the latter from said holder.

3. A slotted piston, an expansible ring mounted within the piston, means acting to hold the ring expanded therein, said means comprising a wedge fitted to a side wall of the piston and means directly affixing the last mentioned means non-adjustably to the piston.

4. A slotted piston having a groove 10 formed internally therein, an expansible ring disposed within the groove, a wedge fitted to the inner wall of the piston and driven between the ends of the ring to expand the same, and means directly connecting the wedge with the piston. 15

In testimony whereof, I affix my signature.
WALTER S. FISHER.
